Atty.

UNITED STATES PATENT OFFICE.

CAMILLE BEZANCON, OF NEW YORK, N. Y.

STEAM-HOIST.

SPECIFICATION forming part of Letters Patent No. 312,423, dated February 17, 1885.

Application filed June 14, 1884. (No model.)

To all whom it may concern:

Be it known that I, CAMILLE BEZANCON, of the city, county, and State of New York, have invented a new and useful Improvement in 5 Steam-Hoists; and I do hereby declare that the following is a full and exact description thereof, reference being had to the accompanying drawings, and to the letters of reference marked thereon, making a part of 10 this specification.

My invention relates to an improved steam hoisting device specially adapted for use upon cranes and derricks to operate the hoisting-tackle thereof by steam.

15 It consists in the direct attachment of the fall in a hoisting-tackle to the rod of the piston of a steam-cylinder attached to or supported by the mast of a derrick or crane of ordinary construction or to other suitable support, so that the inward movement of the piston in the steam-cylinder will operate the hoisting-tackle for the purpose of lifting the load suspended thereto.

20 My device is especially adapted for use in loading and unloading vessels.

25 In the accompanying drawings, Figure 1 is a side elevation of a derrick fitted with my improved steam-hoist, and Fig. 2 a sectional view of a two-way steam-cock used to control 30 the admission and exhaust of steam to and from the steam-cylinder.

35 A is the pole or mast of an ordinary derrick, provided with a boom, B, projecting therefrom, and upheld by a stay rod or rope, C, in the usual manner. The boom B is preferably pivoted and connected at its inner end to the mast A by means of a fork, D, embracing the mast, and whose arms are pivoted to trunnions or pins projecting from a ring, E, 40 encircling the mast.

45 Upon the body of the mast A, and dependent therefrom, is suspended a long steam-cylinder, F, preferably made in sections bolted together to form a continuous chamber. Within this cylinder is fitted a piston, G, from which a piston-rod, H, extends outwardly, in the customary manner, through a stuffing-box in the head of the cylinder. The cylinder is covered by a suitable non-conducting jacket, S, to prevent 50 condensation therein, and is attached for serv-

ice to the mast A by a suspending-hook, J, passing through or itself attached to a ring encircling the mast. The length of the completed cylinder F will be governed by the height to which the load is to be lifted and 55 the number of turns which the hoisting-rope is made to take through the block and tackle, hereinafter described.

To the foot of the mast is attached one of the pulley-blocks, K, of an ordinary block and 60 tackle, and the second block, K', is attached to the end of the piston-rod H. The hoisting-rope, made fast to the lower block, K, is led through the two blocks, with any desired 65 number of turns, and thence through a third pulley-block, K'', suspended to the upper and outer end of the boom B, from which it depends for attachment to the load to be hoisted.

The admission of steam to the cylinder is controlled by means of a two-way cock, M, 70 connected with the steam-boiler by means of a flexible pipe, N, and with the cylinder F by a pipe, O. One passage, m, of the cock is made to admit steam direct from the boiler into the pipe O, to supply the cylinder, and the 75 second passage, n, therein is made to connect said pipe H with an outward exhaust opening or pipe, P. A vent-hole, R, is formed in the outer end of the cylinder F, to prevent the 80 formation of an air-cushion between said piston and the outer cylinder-head.

In the use of the device, the free end of the hoisting-rope being drawn outward for attachment to the load, and the piston thereby carried to the outer end of the cylinder, the hoist 85 is in readiness for operation. So soon as the rope is properly hooked or attached to the load to be moved the two-way cock M is turned so as to admit steam into the lower end of the cylinder, and the consequent movement of the 90 piston H will operate to draw upon the hoisting-rope L, and thereby raise the load.

To lower the load it is only necessary to turn the cock M more or less, so as to permit an 95 exhaust of the steam from the cylinder and allow the piston to move outwardly.

I do not confine myself to the use of a cylinder suspended upon the mast of a derrick, for it is evident that the cylinder may be placed in any convenient position, and be secured to a 100

post or other object, always providing that its axis is in line with the base of the mast, so that the block and tackle will operate readily.

I claim as my invention—

- 5 1. The combination, with the hoisting-tackle in a derrick, of a steam-cylinder and single acting piston connected thereto to operate the same, substantially as and for the purpose set forth.
- 10 2. In a hoisting-derrick, the combination, with its swinging boom and its hoisting-rope, of a double block and tackle for operating said hoisting-rope, actuated by a single acting

piston working within a cylinder suspended upon or connected with the derrick-pole, and a two-way cock for controlling the admission and exhaust of the steam to and from said cylinder, substantially as and for the purpose herein set forth. 15

In testimony whereof I have signed my name 20 to this specification in the presence of two subscribing witnesses.

CAMILLE BEZANCON.
